UNITED STATES PATENT OFFICE.

JOHN ROWLAND BROWN, OF CLEVELAND, OHIO, ASSIGNOR TO THE RELIANCE GAUGE COLUMN COMPANY, OF CLEVELAND, OHIO, A CORPORATION OF OHIO.

GAUGE COCK.

Application filed September 25, 1920. Serial No. 412,788.

To all whom it may concern:

Be it known that I, JOHN ROWLAND BROWN, a citizen of the United States, and a resident of Cleveland, county of Cuyahoga, and State of Ohio, have invented a new and useful Improvement in Gauge Cocks, of which the following is a specification, the principle of the invention being herein explained and the best mode in which 10 I have contemplated applying that principle, so as to distinguish it from other inventions.

The object of my invention is to provide an improved gauge cock which will be free 15 of the defects noted in apparatus of this character heretofore constructed, such as cause the sticking of the valve or misalignment of the valve stem, its guide members, and the valve seat, as well as to provide for 20 improved constructions of the several elements of this apparatus. More particularly, my invention provides for the elimination of one of the guide members customarily used to support the valve stem and to provide 25 but a single guide member for the valve stem apart from the valve seat at its inner end. To the accomplishment of the foregoing and related ends, said invention, then, 30 consists of the means hereinafter fully described and particularly pointed out in the claims.

The annexed drawing and the following description set forth in detail certain mechanism embodying the invention, such 35 disclosed means constituting, however, but one of various mechanical forms in which the principle of the invention may be used.

In the drawing, but a single figure is shown, which is a side elevation, partially in 40 section. A body portion 1 is provided, upon one end of which a cap 2 is secured by screw threaded engagement therewith. The cap is provided with an outwardly extending support for a bell crank lever 3 which is pivotally mounted thereon.

Centrally of the body portion is provided 45 a valve chamber 4. At one side along the longitudinal axis of said valve chamber is provided an inlet passageway 5 and at the 50 opposite side a housing 6 for the valve spring. At the lower portion of the valve chamber is provided an outlet passageway 7 of the usual character. The inlet passageway 5 as it extends toward the valve chamber is of constricted diameter 8 and at its

inner end is provided with a valve seat 9. The wall of the valve chamber has an inwardly extending contour 10 surrounding a recessed or countersunk portion 11 of somewhat larger diameter than the diameter of the valve pin, the lower end of which it surrounds. The space between the valve pin and the walls of the recess 11 is sufficient to permit slight lateral displacement of the pin, but not enough to allow the point thereof to be placed out of registry with the constricted passageway 8, over which the valve seats.

The valve stem 12 extends along the longitudinal axis of the body portion from 70 the valve seat through a central aperture 13 in the cap and is provided with a pivot pin 14 at its outer end for connection with one end of the bell crank lever heretofore mentioned.

The inner end of the valve stem may be 75 provided with a valve pin 15 preferably of a hard non-rusting metal, such as hot rolled Monel metal. When such pin is used I form the same with an annular depression 80 16 near its base and then provide the end of the body portion of the valve stem with a recessed portion 17 into which the base 18 of the valve pin is inserted. The metal at the rim 19 of the recess of the body portion is then spun into the annular depression of the valve pin and the parts are thus held 85 in rigid permanent relation. It will be understood that the term "valve stem" will 90 include the entire structure so formed unless otherwise specified in the claims.

Centrally of its length the valve stem is 95 provided with an annular shoulder 20 preferably by making its inner portion 21 of larger diameter than the outer portion 22 as is clearly shown in the drawing.

The housing for the valve spring heretofore referred to is a chamber formed in the body portion along its longitudinal axis and is separated from the valve chamber by a 100 wall 23, in which is an aperture 24 to permit of the passage of the valve stem. In the usual constructions of this character this aperture forms a guideway for the valve stem with which it has a close sliding fit. In my construction I cut away this contact portion or make the aperture larger initially, so that at no time will the valve stem come 105 into contact with this wall. So far as this function is concerned, the wall may be 110

omitted altogether. The said wall however, serves as a baffle to protect the spring.

Surrounding the valve stem within the valve spring housing is the valve spring 25, 5 at its inner end abutting a washer 26 seated against the shoulder on the valve stem before mentioned, and at its outer end engaging a washer 27 beneath which is placed a packing ring 28 which serves to make a 10 fluid-tight joint with the cap.

The gauge cock is operated in the usual manner, one end of the bell crank lever being pulled down and its opposite end serving to retract the valve stem, thereby lifting 15 the valve pin from its seat and permitting the fluid to pass through the apparatus. Obviously, the fluid may be passed through the apparatus in either direction, depending upon the outside connections, but the 20 usual method of use is the one described.

As will be noted, the valve pin has some freedom of motion in seating because of slight play permitted by the aperture 13 in the cap, which insures a perfect contact and tends to keep it free of obstruction. The recessed or countersunk portion about the valve seat will prevent the valve pin being so displaced as to be entirely out of line with the inlet passageway, but, ordinarily, 30 the valve stem will be held in a central position by the pressure of the spring against its annular shoulder. The valve pin need not be ground into fitting contact with its seat but is given a line contact by 35 lightly tapping it against the seat.

The apparatus herein described is of simple construction and can be assembled without the use of any special tools. It is of unusual wearing quality because of the use of 40 a hard non-rusting metal valve pin and the eliminating of the plurality of guide members which bring about the misalignment of the parts and the evil results attendant upon such defects.

45 Other modes of applying the principle of my invention may be employed instead of the one explained, change being made as regards the mechanism herein disclosed, provided the means stated by any of the 50 following claims or the equivalent of such stated means be employed.

I therefore particularly point out and distinctly claim as my invention:—

55 1. In a gauge cock, the combination of a body having a chamber with inlet and outlet openings, one of said openings being formed with an inwardly flaring valve seat, and a reciprocable valve stem provided with a valve pin adapted to co-operate with said seat, said chamber including a countersunk recess aligned with the seat opening of such diameter that the point of said valve pin cannot be displaced to non-seating position to one side of opening.

60 2. A gauge cock comprising a body por-

tion, having an enlarged expansion chamber centrally thereof, and communicating inlet and outlet passageways to said expansion chamber, a valve seat at the end of one of said passageways, a cap member on said body portion opposite said valve seat, a guide-way provided centrally of said cap member, a valve stem having longitudinal movement through said guide-way and supported against lateral movement solely by said 70 guide-way when retracted from the valve seat, said chamber adjacent said valve seat comprising a countersunk portion or recess to prevent accidental lateral displacement of the point of said valve stem out of registry with the passageway over which said valve stem is adapted to seat.

3. A gauge cock comprising a body portion, having an enlarged expansion chamber centrally thereof, and communicating inlet and outlet passageways to said expansion chamber, a valve seat at the end of one of said passageways, a cap member on said body portion opposite said valve seat, a guide-way provided centrally of said cap member, a valve stem having longitudinal movement through said guide-way and supported against lateral movement solely by said 80 guide-way when retracted from the valve seat, a spring cooperating with said stem to normally keep the same seated, said chamber adjacent said valve seat comprising a countersunk portion or recess to prevent accidental lateral displacement of the point of said valve stem out of registry with the passageway over which said valve stem is adapted to seat.

4. A gauge cock comprising a body portion, having an enlarged expansion chamber centrally thereof, and communicating inlet and outlet passageways to said expansion chamber, a valve seat at the end of one of said passageways, a cap member on said body portion opposite said valve seat, a guide-way provided centrally of said cap member, a valve stem having longitudinal movement through said guide-way and supported against lateral movement solely by said 90 guide-way when retracted from the valve seat, a spring abutment on said stem, a spring interposed between said abutment and the cap member and acting to retain said stem upon its seat, said chamber adjacent said valve seat comprising a countersunk portion or recess to prevent accidental lateral displacement of the point of said valve stem out of registry with the passageway over which said valve stem is adapted to seat.

5. A gauge cock comprising in combination a body portion having an enlarged central expansion chamber, and inlet and outlet passageways in communication therewith, one of said passageways being provided with a valve seat, a cap on said body portion op-

- posite said valve seat, a guide-way provided centrally of said cap, a valve stem mounted in said guide-way for reciprocating movement therein, said stem having a shoulder, a 5 spring interposed between the inner portion of the cap and said shoulder, said valve stem having no point of support intermediate of its ends other than said guide-way, said chamber adjacent said valve seat comprising 10 a countersunk portion or recess to prevent accidental lateral displacement of the point of said valve stem out of registry with the passageway over which said valve stem is adapted to seat.
- 15 6. A gauge cock comprising in combination a body portion having an enlarged central expansion chamber, and inlet and outlet passageways in communication therewith, one of said passageways being provided with 20 a valve seat, a cap on said body portion opposite said valve seat, a guide-way provided centrally of said cap, a valve stem mounted in said guide-way for reciprocating movement therein, an annular shoulder 25 provided centrally of said valve stem, a
- spring chamber provided in said body portion, a baffle flange separating said spring chamber from said expansion chamber and a spring housed within said chamber interposed between the inner portion of the cap 30 and the shoulder on said valve stem, said valve stem having no point of support intermediate of its ends other than said guide-way.
7. A gauge cock comprising a valve chamber, a valve inlet passageway of constricted diameter, a valve seat therein, a valve stem having reciprocating and lateral motion within said chamber, a valve pin rigidly supported upon said valve stem and adapted 35 to be placed in fluid-tight engagement with said seat, said chamber adjacent said valve seat comprising a countersunk portion or recess to prevent accidental lateral displacement of the point of said valve stem out of 40 registry with the passageway over which said valve stem is adapted to seat.

Signed by me, this 23rd day of September, 1920.

JOHN ROWLAND BROWN.
